(57) **CLAIM**

The ornamental design for an extension socket device as shown and described.

DESCRIPTION

FIG. 1 is a perspective view of an extension socket device showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown in the figures are for the purpose of illustrating portions of the extension socket device and form no part of the claimed design.

1 Claim, 7 Drawing Sheets
